United States Patent Office.

EREMIAH MEYER, OF KEARNEY, NEW JERSEY, ASSIGNOR TO JOHN JEWETT & SONS, OF NEW YORK CITY.

Design No. 4,444, dated October 25, 1870.

DESIGN FOR A FLOOR OIL-CLOTH PATTERN.

The Schedule referred to in these Letters Patent and making part of the same.

o all whom it may concern:

Be it known that I, JEREMIAH MEYER, of Kearney, in the county of Hudson and State of New Jersey, have invented a new and original Design for Oil-cloth; and I do hereby declare that the following a full, clear, and exact description thereof, which will enable others skilled in the art to make and use the same, reference being had to the accompanying drawings forming part of this specification.

The nature of my design is fully represented in the accompanying illustration, to which reference is made.

I claim as my invention—

The design for a floor oil-cloth, as shown.

JEREMIAH MEYER.
